UNITED STATES PATENT OFFICE.

GEORGE W. FOSTER, OF PROVIDENCE, RHODE ISLAND.

YARN-PACKAGE AND METHOD OF WINDING SAME.

1,233,041.

Specification of Letters Patent. Patented July 10, 1917.

Application filed February 19, 1916. Serial No. 79,412.

To all whom it may concern:

Be it known that I, GEORGE W. FOSTER, a citizen of the United States, residing at Providence, in the county of Providence,

5 State of Rhode Island, have invented certain new and useful Improvements in Yarn-Packages and Methods of Winding Same, of which the following is a specification.

My invention relates to improvements in 10 cross-wound cone-packages of yarn or other textiles and the method of winding the same. The object of my improvement is to provide a yarn-cone or package from which the material will deliver more freely and evenly, 15 in unwinding it over the end, with a more uniform tension and with less liability of the yarn being strained or broken.

With this end in view my improvement consists essentially in building up the yarn- 20 mass on a conical tube or holder in such manner that the taper of the cone is gradually increased as the winding grows in diameter so that the outer layers are more inclined to the axis of the cone than the 25 inner ones. That is to say, the yarn is built up faster at the large end of the cone than at its small end so that the mass is thicker at the base than at the apex with a corresponding increase in the taper of the layers 30 of winding from start to finish of the cone. The mechanism for building the cone in accordance with the herein-described method is described in my copending application for patent, Serial No. 90,447, filed April 11, 35 1916.

It has before been proposed to wind yarn-cones with a gradually increasing taper from start to finish of the winding, but heretofore this has been accomplished in an entirely 40 different manner from the present improved method. One way of increasing the taper of the cone during the winding is to apply a greater amount of pressure on its surface at the small end than at its base to 45 compact the yarn-mass at the apex; while another method of securing the same result is to wind the yarn with closer coils at the base end than at the apex to build up a greater mass of material at the large end of 50 the cone. This latter method of winding contemplates the changing of the angle of the turns or coils of the yarn in winding from one end of the cone to the other, as described in my United States Letters Patent No. 766,175, granted Aug. 2, 1904. As 55 before stated, the present method of in-

creasing the taper of the cone is entirely different from what has been previously proposed and is an improvement thereover as more fully explained hereinafter.

The manner of carrying out the improvement is fully described in the following specification, illustrated by the accompanying drawings, in which like reference characters designate like parts. In the drawings:

Figure 1 is a view of the completed cone illustrating the increase in the taper of the layers of winding from its interior to its exterior;

Fig. 2, a view of a partly wound cone showing a stage of the winding where the traverse of the yarn is progressively shortened toward the base of the cone to build up a greater thickness of yarn at this end;

Fig. 3, a more or less diagrammatic view illustrating one-half of the cone in section taken on its axis and showing the arrangement of the shortened courses therein; and

Fig. 4, a diagrammatic plotting of the traverse of the windings showing how they are progressively shortened and lengthened at intervals in the building of the cone.

It is to be understood that the term "yarn" as employed in the description is used in a general sense to designate any attenuated material such as fibers, threads, twine, cord, silk, and other strands of a like nature. Referring to the drawings, it is the usual practice to wind yarn and other textiles on conical tubes or holders of paper, fiber, wood or like material which may be either hollow or solid and are generally adapted to fit onto a winding mandrel or spindle. In Figs. 1, 2 and 3 I have illustrated my improved cone C as built up on a hollow paper tube T of conventional taper having its smaller end t rounded over to provide a smooth surface for the yarn to draw across in unwinding from the inner layers. It is of advantage, of course, to employ a tube or holder of relatively great taper in order to facilitate the drawing off of the coils of yarn therefrom in unwinding it, but in practice there is a maximum limit as to the conicality of the holder which must be observed. That is to say, the larger or base end of the cone-tube must be kept within reasonable dimensions, or otherwise it would cause the whole cone-package to bulk too large; and another point to be considered is the maximum taper on which it is

practical to wind the material. In other words, if the taper of the holder on which the first layers of winding are laid is too steep the coils of yarn will slip down out of place and therefore a stable structure can not be secured. It is a well known fact that it is more difficult to maintain the coils in position on a surface of small diameter than on one of large dimension, so that, in accordance with this principle, as the winding increases in diameter the taper of the cone may be increased without detrimental results. In view of this a certain taper for the cone-tube or holder is adopted as a standard and to provide for greater freedom in delivery of the yarn from the outer layers of the cone the inclination of the layers is gradually increased throughout the winding.

In my present improvement I provide for this increase in the taper of the cone by building up more yarn toward its base end than at its small end in the following manner: Referring to Fig. 3, I first wind the yarn on the cone-tube T with a series of layers or courses $c-c$ of uniform length, and preferably the ends of the layers will align in a plane slightly inclined to the axis of the cone, as here shown, so that the base b of the cone will be somewhat convex in form while its smaller or nose end n will assume a concaved shape, see Fig. 1. This concavo-convex shaping of the ends of the cone is not material to the present invention, however, and usually occurs only in "drum-wound" packages, so-called. After a certain thickness of yarn has been laid on the tube T in the above described manner, as indicated by the inclosing lines designated $c'-c'$, $c-c$, in Fig. 3, I commence the shortening of the traverse of the yarn to lay a series of stepped-back courses $l-l$, etc. It will be understood that the yarn winds back to the base end b of the cone at each and every traverse but at the forward or nose end the course of the yarn is progressively shortened from time to time. This shortening of the traverse continues progressively until finally the course of the yarn is considerably less than the full length of the cone, the shortest courses being about one-half the full traverse as illustrated in Figs. 2 and 3. At this point the traverse of the yarn is lengthened again to a slight extent and continues to increase progressively to form the overlapping courses $l'-l'$ as illustrated in Fig. 3. After the traverse attains its maximum length again another series of full courses c^2-c^2 is built up until the cone reaches approximately two-thirds of its full diameter. At this point the traverse of the yarn is once more progressively shortened to wind the stepped courses l^3-l^3 , etc., and then increased progressively to lay the overlapping courses l^4-l^4 until finally the full length of traverse is reached once more in

the layers c^3-c^3 . Thereafter the length of the layers remains constant and the cone is completed to its full diameter with the maximum traverse of the yarn.

Referring still to Fig. 3, it will be seen that the mass of yarn in the cone is thus built up in three overlying sections comprising courses of uniform length separated by intermediate sections consisting of courses of graduated lengths. In this manner the intermediate portions of the winding constitute approximately wedge-shaped masses intervening at different points between the main layers of the cone. The effect of interposing these shortened courses in the cone, as will be readily understood, is to build up more yarn at its base and consequently to increase the taper of the surface on which the winding is being performed. In this way the inclination of the layers of winding in the cone is gradually increased from the interior to its outside for the purpose as previously explained. It will be understood, of course, that where the yarn has a tendency to accumulate in any one part of the mass its natural elasticity or softness will cause it to be smoothed out so that the surface of the cone is kept true and regular throughout all portions of the winding. Furthermore, each shortened course comprises but a relatively small number of coils of yarn, not enough in any instance to complete a full layer, so that there is no appreciable line of demarcation at the ends of the shortened traverses; the definition between the courses of the yarn shown in Fig. 3 being exaggerated to make clearer the method of shortening the traverses. As a matter of fact the preferred practice is to shorten the traverse of the yarn gradually instead of with a step-by-step motion so that each shortened course merges into the next one without any distinction therebetween. It is also to be noted that the manner of proportioning the courses of the winding as here shown is only illustrative of a preferred system, the arrangement being arbitrary and usually determined by experiment as to the method which gives the best results.

Fig. 4 illustrates the progressive shortening and lengthening of the traverse of the windings more graphically and will perhaps give a clearer understanding of the invention. The change in the length of the courses of winding in the cone is effected through an automatic regulation of the length of traverse of the thread-guide which deposits the coils of yarn in place and the method of operation of the guide is as follows: Beginning at the bottom of Fig. 4, the yarn is first traversed the full length of the cone from x to x' , back to x^2 , then to x^3 and so on until a considerable number of layers have been deposited in place, approximately 130

one-third of the whole mass surrounding the tube T as shown in Fig. 3. At this point the traverse of the yarn-guide is automatically shortened to a slight extent and the coils or turns of yarn are laid from a point x^4 at the base of the cone to a point x^5 at the opposite end. After one or more traverses of the yarn have been made to this extent the length of traverse of the yarn-guide is again shortened so that it winds from x^6 to x^7 and after another brief interval it is once more shortened to extend between the points x^8 — x^9 . This reduction in the length of the traverse is repeated from time to time in accordance with any preferred system and eventually the minimum length of traverse is reached at x^{10} — x^{11} . At this point the traverse is increased in length at intervals as shown by the lines x^{12} — x^{13} , x^{14} — x^{15} until finally the full length is reached once more at x^{16} — x^{17} . From this point the winding is performed with traverses of uniform length as represented by the lines x^{16} — x^{17} , x^{17} — x^{18} , etc., until another considerable section has been added to the mass, and the shortening of the traverse is then commenced again and continued as first described.

After another section of shortened courses is added to the winding the traverse assumes its maximum extent once more and the cone is then completed with layers of full length.

While I have herein illustrated my improved cone with two interposed sections of shortened courses, in some instances it may be preferable to provide a greater number to obtain a more gradual sloping of the surface of the winding. Likewise in some cases it might be found expedient to shorten the courses of the yarn clear back to the base of the cone or to arrange them in different relation, but such slight modifications would come within the spirit and scope of the present invention. Therefore, having now fully set forth the object of my improvement and the manner and method of its attainment, what I claim is:—

1. An improved yarn-cone consisting of a series of superimposed layers arranged about a central conical support with portions of the mass wound with a maximum traverse equal to the full length of the cone, and intervening portions composed of courses of yarn-coils of decreasing and increasing length disposed to build the cone with a gradually increased taper in the manner and for the purpose substantially as described.

2. An improved cone-package consisting of a body of yarn or like material wound in crossed helices about an axial tube or core with certain of the courses of the yarn coils laid with a traverse equal to the full length of the cone, and other courses gradually shortened toward the base of the cone at intervals of the winding to cause the mass to

be built up with an increasing taper from its center to its exterior in the manner and for the purpose substantially as described.

3. An improved cone-package consisting of a body of yarn or like material wound in crossed helices about an axial support with the main body of the package composed of complete layers of yarn coils extending the full length of the package, and intervening courses of the yarn progressively shortened and then lengthened at the small end of the cone, to cause the surface of the mass to assume a gradually increasing taper from the interior to the exterior of the cone to adapt the yarn to deliver more freely therefrom.

4. An improved yarn-package wound in the form of a truncated cone with the coils of yarn laid in crossed helices built up in superimposed layers, the majority of the layers extending the full length of the cone, and series of courses of gradually decreasing and increasing length interposed between the sections of the full layers to effect a progressive increase in the taper of the surface of the yarn-mass during the winding of the cone.

5. An improved yarn-package consisting of a body of material built up in the form of a truncated cone and comprising superimposed layers of crossed coils with the major portion of the courses of the yarn extending the full length of the cone, and other courses of the yarn being progressively shortened at the small end of the cone whereby the outer layers of the yarn will have a greater inclination to the axis of the cone than the inner ones.

6. An improved yarn-package consisting of a body of material built up in the form of a truncated cone comprising superimposed layers of crossed coils, with the main portion of the courses of the yarn extending the full length of the cone and intervening courses of the yarn of graduated length extending from the base only part way to the opposite end of the cone and forming substantially wedge-shaped sections interposed in the mass whereby the taper of the cone is greater at its exterior than at its interior.

7. An improved method of winding conical yarn-packages consisting in first winding a series of courses of crossed coils of uniform traverse on a central support, next winding a series of courses of progressively shortened traverse on the first wound mass, then increasing the length of the courses to the maximum traverse again, and repeating the shortening and lengthening of the traverse at intervals to cause the surface of the winding to assume an increasing taper throughout the building of the cone.

8. An improved method of winding conical yarn-packages consisting in laying the yarn in crossed helices on a central support

- with series of courses of a maximum traverse, and intervening series of courses of progressively lessened traverse, said courses of shortened traverses all extending clear 5 to the base end of the cone but stepped back from the opposite or apex end, whereby the cone is built up with a gradually increasing taper from start to finish of the winding.
9. An improved method of winding coni-
10 cal yarn-packages consisting in laying the
yarn in crossed helices on an axial support
with a maximum traverse, and at intervals
of the winding progressively shortening and
lengthening the traverse of the yarn at the
15 small end of the cone, whereby a greater
mass of yarn is deposited at the base end of
the cone than at the opposite end to increase
the taper of the surface of the winding.

from the interior to the outside of the pack-
age.

10. An improved method of winding coni-
cal yarn-packages consisting in first laying
a series of courses of crossed coils on a coni-
cal holder until the winding assumes a pre-
determined diameter, next winding on the 25
yarn in a series of courses with the traverse
progressively shortened toward the base
end of the cone, then progressively increasing
the traverse of the courses until the
maximum is reached, next winding another 30
series of full length courses, again progres-
sively decreasing and increasing the length
of the courses and finally completing the
cone with courses of maximum length.

In testimony whereof I affix my signature. 35
GEORGE W. FOSTER.
